PULVERIZED FUEL FURNACE

Willy Kempf, Cassel, Germany, assignor to
 Stug Kohlenstaubfeuerung Patentverwertung
 G. m. b. H., Cassel, Germany

Application November 13, 1930, Serial No.
 495,491, and in Germany December 13, 1929

3 Claims. (Cl. 110—28)

The invention relates to pulverized fuel furnaces, more particularly on locomotives, and has for its object an improved arrangement of the ignition space of such furnaces.

5 With pulverized fuel furnaces, more particularly when non-gassing coal is used, special fore-chambers are arranged in front of the proper combustion space, in order to obtain with certainty an ignition at the correct time of the fuel-air mixture by preheating it. With the known arrangement of this type which have a comparatively great structural length, the disposition of the fore-chamber on a locomotive is very difficult, due to the very limited space. Now the subject of the invention is an arrangement of the fore-chamber which is remarkable for a simple structure and enables easy disassembling of the fore-chamber from the proper fire chamber and satisfactory utilisation of the latter for the path 10 of the flame, this being of importance especially for locomotive fireboxes which are small and subjected to high load. These objects are obtained by a bodily combination of the ignition chamber with the mixture supply conduit.

25 The drawing illustrates an embodiment of the invention by way of example and shows the parts in consideration in a vertical section.

In this embodiment a common coal-dust and air supply conduit a^1 of a pulverized fuel furnace for locomotives is detachably mounted on a boiler l , in the interior of which is provided a combustion chamber i . In the conduit a^1 is arranged a burner plate in form of a rose plate b^1 . Within the conduit a^1 is situated between this rose plate b^1 and the combustion chamber i an ignition chamber, designated generally by l^1 . This chamber is provided with a lining d^1 which forms a passage e^1 , tapered in the direction of flow, therethrough to a constriction f^1 , where it joins a passage g^1 , which is flared from the constriction f^1 towards the chamber i . In this way a space e^1 of frusto-conical shape is formed. Upon removal of the conduit a^1 from the boiler l , the lining d^1 is likewise withdrawn.

45 The fuel-air mixture streaming through the conduit a^1 towards the combustion chamber i is divided by the rose plate b^1 into numerous fine individual jets. The configuration of the ignition space l^1 causes an abundant heating of the mixture up to ignition temperature, as the tapering portion e^1 of the space l^1 causes a radiation of the heat back to the rose plate b^1 . The conical enlargement g^1 behind the constriction f^1 serves to guide the igniting mixture in a di-

rection so as to uniformly spread in the combustion chamber.

The construction according to the invention is well suited for main and auxiliary burners as well as for square locomotive fireboxes and for 60 boilers with plain or corrugated flues. Of course, the details of construction may differ from the embodiment illustrated in the drawing.

What I claim as my invention is:—

1. In a pulverized fuel furnace, more particularly for locomotives, a combustion chamber, a common coal-dust and air supply conduit, a rose burner plate in said conduit intermediate the ends thereof, and an ignition chamber arranged between said rose burner plate and said combustion chamber, said ignition chamber being provided with a lining which forms a passage tapered in the direction of flow therethrough towards said combustion chamber to a constriction, the inner wall of said passage formed by said lining being 70 adapted to radiate its heat back to said rose burner plate and to heat the mixture up to ignition temperature.

2. In a pulverized fuel furnace, more particularly for locomotives, a combustion chamber, a common coal-dust and air supply conduit, a rose-plate in said conduit intermediate the ends thereof, and an ignition chamber arranged between said rose-plate and said combustion chamber, said ignition chamber being provided with 80 a lining which forms a passage tapered in the direction of flow therethrough towards said combustion chamber to a constriction, the inner wall of said passage formed by said lining being 85 adapted to radiate its heat back to said rose-plate and to heat the mixture up to ignition temperature.

3. In a pulverized fuel furnace, more particularly for locomotives, a combustion chamber, a common coal-dust and air supply conduit, a rose-plate in said conduit intermediate the ends thereof, and an ignition chamber arranged between said rose-plate and said combustion chamber, said ignition chamber being provided with 95 a lining which forms a passage tapered in the direction of flow therethrough towards said combustion chamber to a constriction where it joins a passage which is flared from said constriction towards the combustion chamber, the inner wall of said first-named passage formed by said lining being adapted to radiate its heat back to said rose-plate and to heat the mixture up to ignition 100 temperature.

WILLY KEMPF.
